Attorney.

UNITED STATES PATENT OFFICE.

SAMUEL P. MILLER, OF CHICAGO, ILLINOIS.

SPARK PLUG.

Application filed July 14, 1919. Serial No. 310,613.

To all whom it may concern:

Be it known that I, SAMUEL P. MILLER, a citizen of the United States, and a resident of the city of Chicago, county of Cook, and 5 State of Illinois, have invented certain new and useful Improvements in Spark Plugs, of which the following is a specification.

My invention relates to new and useful improvements in spark plugs and has for 10 its object the provision of a device of this character in which the corrosion of the electrodes will be reduced to a minimum.

Other objects will appear hereinafter.

The invention consists in the combinations and arrangements of parts hereinafter 15 described and claimed.

The invention will be best understood by reference to the accompanying drawings forming a part of this specification, and in 20 which,

Fig. 1 is a perspective view of a spark plug embodying my invention.

Fig. 2 is a central vertical sectional view of a spark plug embodying my invention.

25 Fig. 3 is a front elevational view of my invention.

Fig. 4 is a front elevational view of a modified form of my invention.

The approved form of construction, as 30 illustrated in the drawings, is adapted to be used with the usual and ordinary form of spark plug, comprising a thimble 5 the lower portion of which is threaded, as at 6, for reception by the threaded opening 35 in the engine cylinder. The usual jam nut 7 is employed for threading into the interior of the thimble 5. The usual insulating core 8 is employed having the usual nut 9 and terminal post 10. My invention relates 40 solely to the electrodes and the stems forming the same. The usual stem 11 is used as part of the electrodes, the stem being threaded at its upper end for the reception of the nut 9 and the terminal post 10. Provided 45 adjacent the lower end of the stem 11 is a suitable shoulder 12, preferably made integral with the stem 11, this shoulder 12 being adapted to engage against the shoulder which is usually provided at the upper 50 end of the slot which is provided in the insulating core 8, as will be readily understood. In that portion of the stem 11 which projects downwardly beyond the shoulder 12, I have provided a series of grooves 13 55 and 13', these grooves being shown here as

limited to two, although the number may be increased. Surrounding the lower portion of the stem 11 is a sleeve 14, the upper end of which is crimped to seat in the groove 13. This sleeve 14 is also crimped to seat 60 in the second groove 13', as clearly shown in Fig. 3, this crimping forming a shoulder 15 which extends around the interior of the sleeve. The lower end of the sleeve member 14 extends beyond the end of the stem 65 11 and is also crimped inwardly to form a socket 16 for the purpose of loosely retaining a spherical terminal 17 in the space which intervenes between the lower end of the member 11 and the lower end of the 70 member 14. As clearly shown, the lower end 18 of the member 11 is tapered to form a suitable flowing point. Extending around the sleeve member 14 and formed therethrough are suitable openings 19, said openings 75 19 leading into the interior of the sleeve member 14. Projecting downwardly from the thimble 5 is a suitable bracket 20 having an opening positioned centrally in the lower portion thereof. Threaded into this 80 circular opening is the cooperating electrode stem 11'. This stem 11' has provided at its under surface a suitable slot 21, whereby the stem may be adjusted relatively to the cooperating stem 11. The stem 11' is 85 also provided with a suitable sleeve 14'. Similar grooves 13 and 13' are provided in the stem 11' serving the same purpose as grooves 13 and 13' in the stem 11. A similar spherical terminal 17' is secured in the 90 sleeve 14' in a similar manner to the one secured in the sleeve 14. Similar openings 19' project through the sleeve 14'. In the modified form shown in Fig. 4, in the member 11' I have dispensed with the groove 13' 95 and have provided the interior of the member 14' with threads adapted to cooperate with threads on the member 11', the member 11' being threaded throughout its length and crimped at one end to seat in groove 13. 100 Similarly, on the member 11 I have provided a single groove 13, the interior of the member 14 being threaded to cooperate with the threads provided at the lower end of the member 11. The spherical members 17 105 and 17' are retained in the sleeve members 14 and 14' in a similar manner as already described. Upon the member 14 being threaded upon the member 11, the upper end thereof is crimped so as to seat snugly 110

in the groove 13, thereby locking the sleeve 14 upon the member 11.

In Fig. 2 I have shown a modified form wherein only one slot 13 is provided, the sleeve 14 not being threaded.

By forming the electrodes of the spark plugs as indicated, I have provided a spark plug in which the electrodes have rotating or revolving terminals. This results in a 10 different portion of the terminal being utilized, while the device is in operation and results in keeping the terminals thereof free from corrosion, and distributes wear upon the terminals over the entire surface, thereby 15 eliminating the possibility of pitting. Furthermore, the lower electrode is so constructed as to be adjustable, this feature adding greatly to the efficiency of the device.

20 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

25 Having described my invention, what I claim as new and desire to secure by Letters Patent, is:—

30 1. A spark plug having a pair of electrodes; a sleeve secured to one end of each 35 of said electrodes, there being a space formed between the free end of each sleeve and the adjacent end of the electrode to which secured; and spherical terminals loosely mounted in said spaces, substantially as de- 40 scribed.

45 2. In a spark plug, a pair of electrodes,

each comprising a stem; a spherical terminal loosely mounted on the adjacent ends of each of said electrodes; means of securing said terminals in said position; and means 45 of adjusting said electrodes relatively to each other, substantially as described.

50 3. In a spark plug, a pair of electrodes, each comprising a stem; a shoulder mounted on one of said stems; a sleeve mounted 50 on the adjacent ends of each of said stems; and spherical members loosely mounted on the adjacent ends of said stems, substantially as described.

55 4. In a spark plug, a pair of electrodes having similarly shaped, aligned securing members, and spherical terminals loosely mounted in, and protruding from the adjacent ends of said securing members, one 60 of said electrodes being adjustable relatively to the other, substantially as described.

65 5. A spark plug comprising oppositely disposed electrodes having circumferential grooves about their adjacent end portions; sleeves crimped about said electrodes to engage said grooves; and spherical terminals loosely mounted in said sleeves, the ends of the sleeves being crimped to retain the terminals therein, substantially as described.

70 6. In a spark plug, a pair of electrodes, comprising a pair of stems; a socket mounted on the adjacent ends of each of said stems, and each adapted to retain a spherical terminal loosely mounted therein, substantially as described.

75 In testimony whereof I have signed my name to this specification in the presence of two subscribing witnesses.

SAMUEL P. MILLER.
